DRAINER WITH ROTATABLE DRUM AND
ENCIRCLING BELT FOR CONFINING CANS
THEREBETWEEN

Raymond B. Bentley, Pacific Grove, Calif.

Application April 10, 1945, Serial No. 587,643

6 Claims. (Cl. 226—22)

1

My invention relates to drainers, and more particularly to apparatus for draining the liquid contents from cans during the process of canning solid products, such as fish or the like.

Among the objects of my invention are:

(1) To provide a novel and improved drainer adapted to handle tall cans as distinguished from flat, oval cans such as are customarily employed in the packing of sardines;

(2) To provide a novel and improved drainer which shall permit draining of the cans, without injury to the solid contents thereof;

(3) To provide a novel and improved drainer capable of handling tall cans with efficiency, speed and effectiveness;

(4) To provide a novel and improved drainer of large capacity, capable of handling tall cans;

(5) To provide a novel and improved drainer capable of sustained operation;

(6) To provide a novel and improved drainer which can be readily cleaned and serviced when desired.

Additional objects of my invention will be brought out in the following description of a preferred embodiment of the same, taken in conjunction with the accompanying drawings wherein—

Figure 1 is a side elevational view of apparatus embodying my invention;

Figure 2 is an end elevational view of the same apparatus;

Figure 3 is a view in section of a detail of construction of the apparatus of Figures 1 and 2;

Figure 4 is a segment of the drainer wheel and associated conveyors, in plan view;

Figure 5 is a view in section in the plane 5—5 of Figure 4;

Figure 6 is a view in section in the plane 6—6 of Figure 4.

Broadly considered, my improved drainer embodies a pair of independently movable elements having arcuate surfaces, substantially uniformly spaced from each other, and drive means for independently moving such elements at the same angular velocity. The spacing between the surfaces is such as to snugly receive cans of the size to be drained, whereby when carried along by such moving surfaces, they will be snugly held against self-tipping.

Specifically, and with reference to the drawings, the uniformly spaced surfaces form part of a drainer wheel 4 disposed between the sides of a frame 3 and includes a spoked wheel or drum 5 having a rim 6, such wheel being rotatably supported with its shaft 7 in bearings 9 carried by

2

members 11 of the frame. The shaft extends on one side beyond the frame to provide an extension for the mounting of a drive gear 13.

Surrounding the wheel or drum 5, and included as part of the drainer wheel, is a pair of split rings 15 formed of angle iron. Each ring is affixed to one side of the frame with the split at the highest point thereof, and with its lateral flange 17 directed toward the other ring. When so mounted, the two split rings form spaced halves of a concentric channel about the wheel or drum 5, having an opening at each side thereof at its highest point.

This channel is adapted to receive an open-mesh endless conveyor belt 21 of a length sufficient to encircle a tensioning pulley 23, which is supported above and in the plane of the drainer wheel 4, the belt being held in close contact with the lateral flanges 17, which constitute the floor 19 of the channel, from one end of the channel to the other, by an idler pulley 25 on one side of the opening to the channel and a sprocket drum 27 on the other side of the said opening, the teeth of the sprocket drum being in mesh with the belt for driving purposes.

The spacing between the rim 6 of the wheel or drum and the floor of the channel is slightly less than the height of the cans to be handled by the drainer, while the spacing between the lateral flanges 17 forming the floor of the channel is such as to comfortably receive the ends of such cans, to permit such cans, when inserted in the wheel, to engage the open-mesh belt.

To assure proper centering of the cans with respect to the drainer wheel channel, a pair of guard rails 29 are supported by spacers 31 from the channel. These serve to define the proper path of travel for the cans, and thus guide them in their movement in the drainer wheel.

The tensioning pulley 23 is journaled between a pair of arms 33 affixed to a shaft 35 supported between and adjacent the upper ends of corner members 37 of the frame. This tensioning pulley is urged upwardly by a counterweight 39 on a moment arm 41 affixed to a shaft 43 disposed above the tensioning pulley frame shaft 35 and connected thereto through a sprocket 45 and gear 47.

The degree of tension imparted to the drainer belt 21 is rendered adjustable by slidably mounting the counterweight 39 on its moment arm and fixing such counterweight in an adjusted position by a clamping bolt 49.

The belt drive drum 27 carries an axially mounted sprocket 51 in the plane of the drainer

wheel gear 13, both sprocket and gear being engaged by a common chain 53 in drive connection from a gear box 55 supported above the frame, the gear box in turn receiving power from a driving motor 57 mounted on the upper end of the frame.

An idler sprocket 59 adjustably mounted on an upper cross-bar 61 of the frame, is encircled by the drive chain 53 to assure proper drive engagement between the drum sprocket 27 and the belt. The teeth ratios of the various gears and sprockets involved in the common drive system from the gear box 55 to the wheel 5 and drainer wheel belt 21, is such that the rim 6 of the wheel and the belt 21 will travel at identical angular velocities. Maintenance of this relationship is assured by reason of the fact that the drive to each originates in a common power source, namely the electric motor 57 and associated gear box 55.

The split in the drainer wheel channel and guard rings at the high points thereof provides spaces or openings for the introduction to and discharge from the drainer wheel, of such cans as are to be drained. As a means of assuring smooth and continuous movement of such cans to and from the drainer wheel, I provide a pair of chain conveyors 63 and 65 passing the openings at either side of the wheel.

Structurally, each chain conveyor comprises a supporting strip 67 of metal extending the length of the frame and supported on end cross-pieces 69 and 71 thereof. An endless chain 72 carried on end sprockets 73 and 75 mounted on shafts journaled in bearings carried on brackets 77 and 79 which are affixed to corner frame members, runs lengthwise over such strip and is flanked on the outerside by an angle iron section 81 and on the innerside by a pair of shorter sections 83 to form a conveyor channel, down the middle of which runs this endless chain. The smaller sections 83 are longitudinally separated at the opening to the drainer wheel to provide access to or from the drainer wheel.

The thickness of the chain 72 is slightly greater than the thickness of the channel floor constituted by the lateral flanges of the angle iron sections 81 and 83 from which the conveyor channel is formed, whereby the chain will function as a carrier for such cans as are placed in the channel.

One of the conveyors, namely conveyor 63, will be considered as the loading conveyor for the drainer, while the other conveyor 65 will be considered as receiving the cans from the drainer wheel after draining has been accomplished.

To effect transfer of cans from the conveyor 63 to the drainer wheel at the entering side of the drainer wheel, an angularly disposed deflecting wall 85 is placed across the channel of this conveyor, terminating at the far edge of the opening to the drainer wheel. Such deflecting wall serves to divert the cans from the conveyor toward the drainer wheel for transfer thereto.

To facilitate such transfer of cans, the conveyor chain as it approaches the opening to the drainer wheel, is caused to rise slightly above the high point of the rim 6 of the wheel 5 so as to enlist the aid of gravity. Such rise of the chain is effected by placing fixed wedges 87 and 88 beneath the chain to either side of the opening to the drainer wheel. In conjunction with this, inclines 89 and 91 are placed in the conveyor channel to each side of the chain along the stretch leading up to the opening, such inclines being

of sufficient height to preclude excessive tilting of the cans as they are carried up by the chain. Their movement from the conveyor chain onto the rim of the wheel 5 of the drainer wheel is made gradual by a pair of inclined rails 93 affixed to the strip 67, or to a plate 68 applied thereto.

Once the cans have settled on the rotating rim of the wheel 5, they are guided to the center of the drainer wheel channel by the ends of the guide rails 29, which have been shaped for this purpose, and are held to that position by such rails as the cans are carried around by the drainer wheel. Before the cans have an opportunity to be carried very far by rotation of the wheel 5, the upper ends of the cans are engaged by the belt 21 and clamped between this belt and the rim 6 of the wheel 5 in such manner as to securely hold the cans against toppling, in their movement with the drainer wheel.

20 The cans being slightly higher than the distance between the wheel rim 6 and the channel floor on which the belt normally rides when the wheel is empty, the flexibility of the belt and the tensioning mechanism will permit of the lifting of the belt from the channel floor to the extent necessary to effect such grip on the cans.

Obviously, the cans in their travel in the drainer wheel, will be turned bottom-side up, and by reason of the open-mesh construction of the belt, will be given an opportunity to drain themselves of liquid content into a suitable tank 94, to the exclusion of any solid matter packed in the cans, which is held therein by the belt and without damage. As the cans approach their starting position on the drainer wheel, they will be open-end up and ready for discharge onto the conveyor 65, disposed on the discharge side of the drainer wheel. Such discharge is effected by providing a deflecting wall 95 extending between the two conveyor channels across the surface of wheel 5 and connecting diagonally opposite points of the drainer wheel channel.

The discharge channel is disposed in a plane slightly below the high point of the wheel rim 6 to enlist the aid of gravity in making the transfer. Transfer of the cans from the rim to the conveyor chain is, like in the previous instance, eased by the provision of a pair of inclined rails 97 affixed to the strip 67 over which the conveyor chain runs.

55 The chains 72 of the loading conveyor 63 and the discharge conveyor 65, preferably have the same linear velocity imparted to them by a chain 101 linking the gear box 55 with a sprocket 99 on the shaft of the conveyor sprocket 75, and such linear speed is preferably of the order of that of the rim 6 of the wheel 5.

It is apparent that as the cans approach the discharge position on the drainer wheel, the drainer belt is automatically lifted therefrom, thus freeing the cans for discharge. The clamping effect of the belt upon the cans is very important in connection with the draining of tall cans, which would otherwise be very unstable under the conditions encountered.

70 The apparatus as described fully satisfies all the objects of my invention as previously set forth, and while I have disclosed a preferred embodiment of my invention in great detail, the same is subject to alteration and modification, without departing from the underlying principles involved, and I accordingly do not desire to be limited in my protection to the exact details as illustrated and described, except as 75 may be necessitated by the appended claims.

I claim:

1. A drainer comprising a frame; a drainer wheel within said frame and including a wheel or drum rotatably supported by said frame, a channel supported by said frame concentric with and surrounding said wheel, and spaced therefrom by a distance slightly less than the height of a can to be drained, said channel being split at the top and having a peripheral slot slightly greater in width than the diameter of a can, and extending the full periphery of said channel; a drainer belt encircling said channel in contact therewith in the absence of cans in said wheel; means for driving said wheel at a predetermined angular velocity; and means for moving said belt around said channel at the same angular velocity.

2. A drainer comprising a frame; a drainer wheel within said frame and including a wheel or drum rotatably supported by said frame, a channel supported by said frame concentric with and surrounding said wheel, and spaced therefrom by a distance slightly less than the height of a can to be drained, said channel having a peripheral slot slightly greater in width than the diameter of a can, and extending the full periphery of said channel, and a drainer belt encircling said channel in contact therewith in the absence of cans in said wheel; means for driving said wheel at a predetermined angular velocity; and means for moving said belt around said channel at the same angular velocity.

3. A drainer comprising a frame; a drainer wheel within said frame and including a wheel or drum rotatably supported by said frame, a channel supported by said frame concentric with and surrounding said wheel, and spaced therefrom by a distance slightly less than the height of a can to be drained, said channel being split at the top and having a peripheral slot slightly greater in width than the diameter of a can, and extending the full periphery of said channel, a pair of spaced guide rails supported between said wheel and said channel in alignment with said channel, and a drainer belt encircling said channel in contact therewith in the absence of cans in said wheel; means for driving said wheel at a predetermined angular velocity; and means for moving said belt around said channel at the same angular velocity.

4. A drainer comprising a frame; a drainer wheel within said frame and including a wheel or drum rotatably supported by said frame, a channel supported by said frame concentric with and surrounding said wheel, and spaced therefrom by a distance slightly less than the height of a can to be drained, said channel being split at the top and having a peripheral slot slightly greater in width than the diameter of a can, and extending the full periphery of said channel, and a drainer belt encircling said channel in contact

therewith in the absence of cans in said wheel; means for driving said wheel at a predetermined angular velocity; means for moving said belt around said channel at the same angular velocity; a feeding conveyor along one side of said drainer wheel adjacent the split therein; a discharge conveyor along the other side of said drainer wheel adjacent the split therein; and means for deflecting cans from said feeding conveyor to said drainer wheel and from said drainer wheel to said discharge conveyor.

5. A drainer comprising a frame; a drainer wheel within said frame and including a wheel or drum rotatably supported by said frame, a channel supported by said frame concentric with and surrounding said wheel, and spaced therefrom by a distance slightly less than the height of a can to be drained, said channel being split at the top and having a peripheral slot slightly greater in width than the diameter of a can, and extending the full periphery of said channel, and a drainer belt encircling said channel; means for driving said wheel at a predetermined angular velocity; means for moving said belt around said channel at the same angular velocity; and automatic tensioning means for yieldably maintaining said drainer belt in contact with said channel in the absence of cans in said wheel.

6. A drainer comprising a frame; a drainer wheel within said frame and including a wheel or drum rotatably supported by said frame, a channel supported by said frame concentric with and surrounding said wheel, and spaced therefrom by a distance slightly less than the height of a can to be drained, said channel being split at the top and having a peripheral slot slightly greater in width than the diameter of a can, and extending the full periphery of said channel, and a drainer belt encircling said channel; automatic tensioning means for yieldably maintaining said drainer belt in contact with said channel in the absence of cans in said wheel; means for driving said wheel at a predetermined angular velocity; means for moving said belt around said channel at the same angular velocity; conveyor means for feeding cans to the rim of said wheel at one point; conveyor means for receiving cans from said wheel at another point; and means for moving both said conveyor means at approximately the linear velocity of said wheel rim.
